No. 830,974.

PATENTED SEPT. 11, 1906.

F. L. DECARIE.

GAS CONSUMING FURNACE FOR CREMATORIES.

APPLICATION FILED NOV. 21, 1904.

UNITED STATES PATENT OFFICE.

FELIX L. DECARIE, OF MINNEAPOLIS, MINNESOTA, ASSIGNOR TO DECARIE MANUFACTURING COMPANY, OF MINNEAPOLIS, MINNESOTA, A CORPORATION OF MINNESOTA.

GAS-CONSUMING FURNACE FOR CREMATORIES.

No. 830,974.

Specification of Letters Patent.

Patented Sept. 11, 1906.

Application filed November 21, 1904. Serial No. 233,619.

To all whom it may concern:

Be it known that I, FELIX L. DECARIE, a subject of the King of Great Britain, residing at Minneapolis, in the county of Hennepin, State of Minnesota, have invented certain new and useful Improvements in Gas-Consuming Furnaces for Crematories, of which the following is a specification.

This invention relates to improvements in crematories, and more particularly to that class designed for burning the garbage and refuse of cities and towns; and the object I have in view is to provide an auxiliary gas-consuming furnace which may be located between the combustion-chamber of the crematory and the smoke-stack and through which all gases and smoke not consumed in the combustion-chamber of the crematory must pass, and in which they will be fully consumed, and in which any solid particles being carried along by the current of gases will be collected, thereby rendering it impossible for noxious odors or gases to escape through the smoke-stack.

The invention consists generally in the constructions and combinations hereinafter described, and particularly pointed out in the claims.

In the accompanying drawings, forming part of this specification, Figure 1 is a longitudinal section of a gas-consuming furnace embodying my invention. Fig. 2 is a detail of the preliminary gas-consuming chamber, the section being taken on line *xx* of Fig. 1.

In the drawings, 2 represents the casing of the furnace, and 3 is the smoke-stack. A preliminary gas-consuming chamber 4 is located between the combustion-chamber of the crematory and the diving-flue 5 of the furnace. This preliminary chamber is of greater area than the flue, and it is provided with a series of tile 4', that are arranged in said chamber with passages between them. The furnace is provided with the upright walls 6, 7, 8, and 9, all extending upward from the bottom of the furnace, and with the depending walls 10, 11, and 12. The walls 10 and 11 are arranged opposite the walls 6 and 7. The wall 8 extends above the top of the space between the walls 7 and 10, and the wall 12 projects downward below the top of the wall 8. A tortuous passage is thus formed from the preliminary gas-consuming

chamber 4 to the smoke-stack 3. Between the walls 6 and 7 I provide an ordinary fuel-grate 13, and between the walls 10 and 11 I provide a downdraft-grate 14. The grate 14 may be of any suitable construction, although I prefer to use a tubular water-circulating grate. An open water-tank 15 is located at the bottom of the diving-flue, the top of the tank being preferably substantially flush with the top of the wall 6. A similar tank 16 is located between the walls 8 and 9 and a tank 17 at the bottom of the smoke-stack, the tops of the tanks 16 and 17 being preferably substantially flush with the top of the wall 9. I also prefer to provide near the bottom of the wall 12 a transverse perforated pipe 18, that is perforated along its under surface and through which a sheet of water passes from said pipe to the tank 16.

The operation of the apparatus is as follows: The tile 4' in the preliminary chamber 4 being near to the combustion-chamber of the crematory are raised to a high heat by the heat from said combustion-chamber. The vapors and gases from the material being consumed in the combustion-chamber of the crematory pass between these tile and 80 the gaseous current is broken up and raised to a great heat. The currents of gases passing between these tile impinge upon the wall of the diving-flue opposite said chamber. They are deflected by said wall and pass 85 downward, striking the surface of the water in the tank 15. A large portion of the solid or unconsumed material from the combustion-chamber is collected in this tank. I find that a large percentage of the material 90 collected in this tank is combustible and after being dried it may be burned. The gases and vapors pass from the bottom of the diving-flue between the two fires upon the upper and lower grates. The flames from 95 the fuel upon these grates pass in substantially parallel sheets through the tortuous passage over the top of the wall 8, and the gases and vapors that enter from the diving-flue are held between these parallel sheets of flames, where they are superheated and consumed. After passing over the wall 8 the gases take a downward course and impinge upon the surface of the water in the tanks 16 and 17, and they also pass through the sheet 105 of water above the tank 16. By this means

any remaining solid material, such as dust or cinders, is collected in the tanks 16 and 17. The space between the walls 7 and 8, which is below the line of passage of the flame from the lower grate, forms a dead-air chamber, and the sheet of flame passing over this dead-air chamber creates a partial vacuum therein. Solid particles, such as cinders and dust, carried by the current of gases impinging upon the wall 8 fall backward and downward and collect in this space. This space between the walls 7 and 8 forms a dust and cinders collecting chamber 8'.

By employing this auxiliary gas-consuming furnace in connection with a crematory, such as that shown and described in reissued Letters Patent of the United States, No. 12,059, dated November 25, 1902, or in Letters Patent of the United States, No. 749,269, dated January 12, 1903, of both of which I am the inventor, I find that all noxious gases and odors passing from the combustion-chamber of the crematory are completely consumed and the gases passing from the smoke-stack are entirely odorless. I also find that all dust and cinders and solid particles passing from the combustion-chamber will be collected in the water-tanks and in the chamber 8'. The material can be removed from said tanks, and that which collects at the tank in the bottom of the diving-flue, which is mainly combustible, may be dried and burned.

I do not limit myself to the details of the construction, as the same may be varied in many particulars without departing from my invention.

I claim as my invention—

1. The combination, in a gas-consuming furnace, with the lower updraft-grate and the upper downdraft-grate spaced from each

other, of means for conducting gases and products of combustion between the fires upon said grates.

2. The combination, in a gas-consuming 45 furnace, with the lower updraft-grate and the upper downdraft-grate spaced from each other, of means for conducting gases and products of combustion between the fires upon said grates, and means for collecting 50 the solid particles moving through said furnace with said gases and products of combustion.

3. The combination, in a gas-consuming 55 furnace, with a series of walls forming a tortuous passage through said furnace, of a lower updraft-grate and an upper downdraft-grate, said grates being located upon opposite sides of said passage, for the purpose specified.

4. The combination, in a gas-consuming 60 furnace having a passage extending therethrough, of a lower updraft-grate and an upper downdraft-grate, said grates being located upon opposite sides of said passage, for 65 the purpose set forth.

5. The combination, in a gas-consuming 70 furnace having a passage therethrough, of the lower updraft-grate and the upper downdraft-grate arranged upon opposite sides of 75 said passage, the wall 8 arranged opposite the spaces between said grates, and wall 7 forming with the lower part of the wall 8 and the side walls of the furnace the dead-air chamber 8', for the purpose set forth.

In witness whereof I have hereunto set my hand this 2d day of November, 1904.

FELIX L. DECARIE.
